CLAIM

The ornamental design for an extension kit for storage device, as shown and described.

DESCRIPTION

FIG. 1 is a front perspective view of an extension kit for storage device showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof; and,

FIG. 8 is a rear perspective view thereof.

The evenly dashed broken lines in the figures depict portions of the extension kit for storage device that form no part of the claimed design.
